METHOD OF AND APPARATUS FOR CLEANING WOOD CHIPS AND THE LIKE

Sven Rahmberg, Wallvik, Sweden; Axel Bostrom and Martin Rahmberg executors and administrators of the estate of said Sven Rahmberg, deceased

Application November 19, 1934, Serial No. 753,691
In Sweden December 11, 1933

8 Claims. (Cl. 209—21)

This invention relates to a method of and apparatus for cleaning wood chips of the type customarily prepared for treatment in digesters for the making of paper pulp, and for other similar materials.

The presence of sawdust in digesters is highly objectionable, as is also the presence of specks of dirt, bark, or other impurities in pulp which is to be made into high grade papers. Hence, chips should be thoroughly cleaned before entering the digester. It is customary, in preparing wood for digesters, to cut the wood by means of a chipper into chips which average about $\frac{3}{4}$ inch square. After the wood has been run through the chipper, the chips are often run through a crusher so as to break up over-size chips or splinters. According to common practice, the chips are run into a cylindrical screen drum or shaking screens either directly from the chipper or from the crusher. The ordinary type of screen drum is rotated on an inclined axis, the upper portion of it being provided with holes about $\frac{1}{4}$ inch in diameter for the escape of sawdust and other undesirable matter. It is found that holes of this size permit the escape of small chip fragments and splinters which are valuable as material for pulp, but which are lost with the sawdust. Furthermore, the ordinary screens now in use fail to effect a complete separation of dirt and sawdust from the chips, especially if the chips are moist or have adhering thereto bits of bark and the like which are rich in rosin. Particular trouble is often experienced with the thin black bark surrounding the knots in the wood, this bark breaking up into fine pieces in the chipper and tending to adhere to the chips. Such fragments cause specks in the paper ultimately made from the pulp, which are objectionable particularly in the better grades of paper.

According to the present invention, the chips are subject to a treatment which not only effectively cleans the chips but also results in a saving of substantially all of the small chips and splinters which are customarily lost through the chip screens now in common use. According to the invention, the chips are tumbled in a rotating screen drum having openings about $\frac{1}{8}$ inch in diameter. A number of fine blast jets of fluid, such as air, steam, or an equivalent, are projected from near the axis of the screen toward the inner surface thereof. These fluid jets, which are preferably of high velocity, impinge on the tumbling chips and dislodge therefrom all impurities, including dirt, sawdust, bits of bark,

and the like. Suitable means is employed to promote and accelerate the flow of cleaning fluid through the meshes or holes of the screen so that all the loose particles of sawdust or foreign matter are at once expelled from the interior of the screen drum. If desired, apparatus may be provided for separating the chips of proper size not only from sawdust and dirt but also from large splinters of wood which may come from the chipper.

For a more complete understanding of the invention, reference may be had to the following description of an embodiment thereof and to the drawings, of which—

Figure 1 is a longitudinal sectional view of apparatus embodying the invention.

Figure 2 is a section on the line 2—2 of Figure 1.

Figure 3 is a diagrammatic plan view of an installation of apparatus embodying the invention.

Figure 4 is a longitudinal sectional view of a screen drum for separating large splinters from the chips in conjunction with the cleansing thereof.

Figure 5 is a section on the line 5—5 of Figure 4.

The invention may be embodied in a hollow screen drum 10. The screen may be of woven wire or of perforated sheet metal, the openings 30 in either event being preferably about $\frac{1}{8}$ inch in diameter and as closely spaced as is practicable. As shown, the screen drum may be in the form of an approximate cylinder, preferably increasing somewhat in diameter from the supply end 35 to the discharge end. The screen drum 10 is mounted for rotation on a suitable shaft 11, this shaft being journaled in bearings 12 and 13 carried by a frame 15. The portion of the shaft 11, which extends through the bearing 12 and 40 through the entire length of the screen drum 10, is preferably hollow, the hollow portion terminating in a reduced portion 16 which is journaled in the bearing 13. Projecting from the hollow shaft 11 at a suitably large number of points are 45 blast nozzles 20. These nozzles may for the most part be directed radially with respect to the axis of the shaft 11 and screen drum 10. The blast nozzles adjacent to the ends of the screen drum 10 are preferably inclined toward the 50 middle of the screen as at 21 and 22. All of these blast nozzles communicate with the hollow interior of the shaft 11, so that fluid supplied to the shaft 11 under pressure is projected through the various nozzles toward the inner surface of 55

the screen. The screen may have cylindrical extensions 25 and 26 of sheet metal at its ends. On the interior surface of the screen 10 there may be any convenient number of helical fins or ribs 27 which extend to impart axial movement to the chips which are tumbling within the rotating screen drum. The cylindrical extension 25, which, as indicated in Figure 1, is at the supply end of the screen, may be provided with similar fins 28. Chips to be cleaned may be introduced into the extension 25 of the screen drum as by a chute 30 which leads through a stationary end plate 31. At the opposite or discharge end of the screen drum is an end plate 32 having a discharge opening 33 therein. This opening may be of any convenient size, shape and location, such, for example, as illustrated in Figure 2.

The screen is located within a casing which 20 may be made approximately air-tight. This casing may be of suitable size and construction as desired. As shown in Figure 1, the casing is approximately barrel-shaped, having a pair of frusto-conical portions 35 and 36 which are connected by a circumferential channel member 37. The circumferential channel in the member 37 communicates with an outlet or suction vent 40 through which the cleaning fluid which enters the screen through the nozzles 20, 21 and 22 may be 25 sucked from the interior of the casing. In the structure illustrated in Figure 1, the imperforate extensions 25 and 26 of the rotating screen drum project from the ends of the casing portions 35 and 36 and hence act as portions of the casing, together with the end plates 31 and 32. Sufficient clearances are preferably left between the stationary heads 31, 32 and the moving parts 25, 26, and also between the stationary channel member 37 and the adjacent moving portions of the drum to ensure free rotation of the drum. The casing 30 is thus nearly air-tight except for the supply chute 30, the discharge opening 33, the nozzles 20, 21 and 22, and the suction vent 40 so that a strong suction can be maintained through the meshes or holes of the screen 10. As indicated in Figure 3, the screen drum 10 may be rotated by means of a suitable power-transmission device such as a gear wheel 50 which is mounted on the reduced end portion 46 of the shaft 11 and which meshes with a pinion 51 mounted on the shaft 45 of a motor 52. Air or other cleaning fluid may be supplied to the hollow shaft 11 by means of a connecting pipe 55 leading from a suitable air pump 56 driven by a motor 51. The suction vent 50 may be suitably connected to a pump 60 which 55 may be driven by a motor 61. Any other desired driving means may be employed for rotating the screen and for operating either or both of the pumps.

In operating the mechanism, the screen drum 60 may be rotated at any suitable speed, depending on its diameter, the speed of rotation of a 5-foot screen drum being preferably from 10 to 15 R. P. M. Wood chips to be cleaned are supplied 65 through the chute 30 directly from the chipper, or from a conveyor, or from any other suitable source. The chips enter the end compartment adjacent to the smaller end of the screen drum and are moved along axially by the helical fins 70 28 as the screen drum is revolved. These fins also assist in tumbling the chips thoroughly within the screen as they progress from the supply end thereof to the discharge end. During their progress through the screen drum, tumbling chips 75 are subjected to blasts of cleaning fluid, such as

air, which is pumped into the hollow shaft 11 and is discharged through the nozzles 20, 21 and 22, preferably at high pressure. These nozzles are preferably of comparatively small diameter so that, although the cleaning fluid is projected at high velocity into the interior of the screen, the total volume of fluid thus entering the screen is not excessive. The flow of cleaning fluid outwardly through the perforations of the screen is expedited by suction maintained on the vent 40 10 as by a suction pump 60. As indicated on the drawings, the cross sectional area of the vent 40 is large in comparison with that of the individual nozzles 20 so that the air or other fluid discharged at high velocity but in relatively small volume 15 through the nozzles 20 is readily carried off by the vent 40. This pump is preferably of such capacity as to be capable of maintaining the pressure in the space between the screen 10 and the casing members 35 and 36 somewhat below atmospheric pressure, if desired, so that there may be a slight inflow of air through the chip supply and discharge openings in the casing. The skin friction of the rotating screen causes a rotary flow of the air within the casing in the direction 20 of rotation of the screen itself, this air also tending to flow toward the channel 37 and thence out through the vent 40, carrying with it the sawdust and dirt particles which have been dislodged from the chips by the blasts of air or other cleaning 25 fluid from the nozzles. The inclination of the nozzles 21 and 22 toward the middle of the screen tends to drive the dirt-laden air within the screen drum toward the middle of the screen to pass through the screen opposite the channel 37 and the suction vent 40, and also tends to prevent flow of air toward the chip supply and discharge openings in the ends of the casing. The chips, after progressing from the supply end of the screen to the discharge end, fall through the discharge 30 opening 33 and are caught by a receptacle or conveyor (not shown).

In the chipping process as ordinarily practiced, the pulp-wood logs are fed to the chipper at an angle so that the knives of the chipper strike obliquely across the grain of the wood. It frequently happens that a log which is nearly all cut will turn so that the chipper blades cut it lengthwise, this resulting in large slivers which are undesirable for the digester. According to the present invention, such large slivers can be separated from the chips simultaneously with the cleaning operation. To this end, I may provide apparatus such as is illustrated in Figures 4 and 5. This embodiment of the invention may include a revoluble drum 70, similar to the drum 35, with an extension 71 at the supply end rotating against an end plate 72 and having oblique ribs 73 to feed the chips received through the chute 30. A suction channel 77 surrounds the mid-periphery of the drum 70 where the halves of the drum are separated, this channel leading to suction outlet 78 which preferably leads to a suitable pump as illustrated in Figure 3. If desired, suitable flexible strips 79 may be carried by the channel 77 to bear against the adjacent portions of the rotating drum 70 so as to close the clearance between these parts.

Within the drum 70 and rotatable therewith, are a pair of coaxial screens 80 and 81, the outer screen 80 having relatively small openings therein, the inner screen 81 having larger openings. For example, the screen 80 may have openings varying from $\frac{1}{8}$ inch at the supply end to about $\frac{1}{4}$ inch at the opposite end thereof. The inner

screen may have openings varying from about $\frac{1}{8}$ inch at the supply end to 1 or 2 inches at the other end. These aperture sizes and those hereinafter given are by way of example only and not by way of limitation. The screens 80 and 81 preferably diverge somewhat in diameter toward the discharge end. Beyond the discharge end of the drum 70 is an imperforate extension 83 which may be substantially a continuation of the screen 10 member 80. The extension 83 revolves with the drum 70 and terminates in an open discharge 15. The inner screen 81 extends through the interior of the extension 83 and projects a substantial distance beyond the discharge end thereof, this portion of the screen 81 having large 20 perforations or meshes of the order of 1 or 2 inches. To promote axial movement by the chips in the drum, helical ribs 85 may be mounted on the inner surface of the screen 80 and drum extension 83 as indicated.

Chipped wood is received by this apparatus direct from the chipper and is at once subjected to the cleaning action of high-velocity jets of fluid such as air, steam or an equivalent. The 25 particles of sawdust and dirt dislodged by the jets are immediately sucked through the meshes of the screen 80 and are discharged through the cutlet 78. The chips and slivers of proper size pass through the meshes or perforations of the 30 screen 81 as they travel toward the discharge end. The oversize fragments remain within the screen 81 until discharged through its open end beyond a partition wall conventionally indicated at 87. The cleaned chips of proper size are discharged 35 from the end of the extension 83 on the rear side of the near side of the partition wall 87 and are then ready for delivery to a digester.

It is evident that various modifications and changes may be made in the embodiment of the 40 invention herein shown and described without departing from the spirit or scope thereof as defined in the following claims.

I claim:

1. A method of cleaning wood chips and the 45 like, which comprises tumbling the chips in a rotating hollow screen drum, projecting fluid jets radially from near the axis of the drum toward the inner surface thereof, and projecting fluid jets from near the axis at points adjacent to the 50 ends of the screen obliquely toward the middle of the drum.

2. A method of cleaning wood chips and the 55 like, which comprises tumbling the chips in a rotating hollow screen drum, projecting fluid jets from near the axis of the screen drum toward the inner surface thereof, including jets adjacent to the ends of the screen and inclined toward the middle thereof, and maintaining a lower than atmospheric pressure at the outer surface of the 60 screen.

3. A method of cleaning wood chips and the 65 like, which comprises continuously feeding chips into one end of a hollow screen drum, continuously rotating the drum, permitting chips to escape from the opposite end of the drum, and

projecting fluid jets from near the axis of the drum toward the inner surface thereof, including jets adjacent to the ends of the screen inclined toward the middle thereof.

4. Apparatus for cleaning wood chips or the like, which comprises a barrel-shaped casing having end-openings for supply and discharge of chips and a suction vent midway between the ends, a hollow rotatable shaft extending through said drum from end to end, a hollow screen drum 10 mounted on said shaft coaxially therewith, and a plurality of jet nozzles on said shaft communicating with the interior thereof, some of said nozzles being adjacent to the ends of the screen and being inclined toward the middle thereof. 15

5. Apparatus for cleaning wood chips or the like, comprising an elongated approximately cylindrical screen rotatable on a horizontal axis, said screen having openings therethrough of sufficient size for the passage of standard chips, 20 means for introducing chipped wood into one end of said screen, an outer screen coaxially surrounding a portion of the first said screen and extending for a portion of the length thereof from the supply end, said outer screen having 25 relatively small openings, means for projecting jets of fluid radially from near the axis of said outer screen, and means for maintaining suction at the outer surface of said outer screen.

6. A method of cleaning wood chips, which 30 comprises tumbling the chips in a rotating screen drum, subjecting the tumbling chips to a series of jets of gaseous fluid at sufficiently high velocity to dislodge from the chips particles of matter adherent thereto, and maintaining a 35 lower than atmospheric pressure surrounding the sides of the drum, whereby discharge of said gaseous fluid through the ends of the drum is avoided.

7. Apparatus for cleaning wood chips, comprising a rotatable screen drum having openings in the sides thereof approximately $\frac{1}{8}$ inch in diameter, a casing enclosing said drum and having apertures for the admission of chips into one end of the drum and the discharge of chips from the other end of the drum, means within the 45 drum for projecting a series of fluid jets toward the inner surface of the screen, and means for maintaining in said casing a lower than atmospheric pressure, whereby discharge of fluid from 50 said jets through said apertures is avoided.

8. Apparatus for cleaning wood chips or the like, which comprises a barrel-shaped casing having end-openings for supply and discharge of chips and a suction vent midway between the ends, a frusto-conical hollow screen drum tapering in diameter from the discharge end of the drum to the supply end and rotatable on its axis, helical fins secured to the inner face of the screen to rotate therewith whereby to assist the chips 55 in their advance toward the discharge end-opening, and means for projecting jets of fluid radially from near said axis toward the inner surface of the screen. 60

SVEN RAHMBERG.
